FIG-2

Technical drawing of a mechanical assembly, likely a pump or valve mechanism, with various numbered components labeled 100 through 118 and 125 through 155. The drawing shows a central vertical shaft with a gear assembly, a piston at the bottom, and various valves and seals. A detailed view of a valve component is shown in the lower right corner.

SHELL FEEDING MECHANISM FOR CANNONS

Sigmund Schiff, Cincinnati, Ohio, assignor to
United States of America as represented by the
Secretary of War

Application December 18, 1945, Serial No. 635,819

25 Claims. (Cl. 89—33)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to means for feeding ammunition to guns of heavy caliber. More particularly the invention pertains to mechanism for feeding rounds of ammunition to automatic and semiautomatic weapons.

There are several instances in the recent development of, and military requirements in, heavy caliber weapons wherein the tendency is toward a design characterized by one-man control of the loading, aiming and firing operations. One particular example is that in which a heavy caliber weapon is mounted in aircraft and is arranged to be operated by the aircraft pilot. In these circumstances it is desirable that the weapon be either completely or preferably semiautomatic. The successful design and operation of a weapon having this latter characteristic requires that operations necessary to condition the weapon for firing—such as extraction and ejection of the cartridge case of a previously fired round and feeding and loading of a new round—be performed in such a manner that the operator has only to actuate the firing mechanism; in short, so that all functioning of the weapon occurs in response to a single control means that involves only a single operation by the operator, whether such functioning is either automatic or semiautomatic as these terms are understood in military parlance.

In my copending application, Serial Number 635,818, filed December 18, 1945, I have disclosed a semiautomatic weapon of the type referred to which includes a simple firing circuit under the manual control of the pilot of an airplane, for example, which circuit is effective to initiate means for feeding rounds of ammunition successively to loading position and to load these rounds into the breech in successive firing cycles. The present invention pertains to a single component of such an automatic weapon; namely, the mechanism for feeding rounds of ammunition successively to positions from which they may be loaded or delivered into the breech of the weapon. As will be hereinafter more clearly brought out, the preferred embodiment of the invention herein disclosed is particularly adapted for use in conjunction with automatic weapons mounted in aircraft and, specifically with weapons of comparatively heavy caliber, e. g., 75 mm. or 105 mm.; however, as will be clear to those skilled in the art, various desirable features of the invention are similarly applicable for adaptation to and use with weapons of smaller or larger caliber and weapons otherwise mounted, as for example, permanently emplaced weapons or weapons mounted in vehicles or ships.

2

The invention has for its principal object the provision of means by which rounds of ammunition may be individually and successively fed or delivered from a position in a magazine or shell-carrying means to a loading position from which they may be successively fed into a gun for firing; in this respect it is specifically an object of the invention to adapt the feeding mechanism for use in a semiautomatic weapon in which such feeding mechanism constitutes a component in the feeding, loading and firing cycle.

It is an important object of the invention to provide such feeding mechanism for a weapon of the recoiling type and to provide means by which the mechanism may be operated by power received from the recoiling gun.

Another important object of the invention is to provide shell-delivery means mounted for movement from a position out of the path of recoil of the weapon to a position breechwardly of the weapon so that a shell may be delivered from a series of shells adjacent the weapon in a manner that will not interfere with normal recoil movement of the weapon.

Other objects of the invention are to provide shell-carrying means for supporting a series of shells adjacent the weapon; to provide means operable in response to recoil of the weapon to deliver shells from the shell-carrying means to a shell-delivery means; to provide means for advancing the series of shells so that the next shell in the series is positioned for delivery by the delivery means in the next successive feeding cycle; to provide power means particularly in the form of energy-storing means capable of being loaded by power received from the gun in recoil and arranged for reaction to operate the feeding mechanism after the weapon has returned to battery; to provide shell-delivery means in the form of a swinging shell tray that includes means thereon for retaining the shell therein until the delivery of the shell into the breech of the weapon is completed; to provide mechanism on the shell-supporting means cooperable with the shell-retaining means for insuring the proper retention of individual shells in the shell tray; and to provide means for insuring the proper feeding of shells at a cyclic rate determined by the firing cycle of the weapon.

The foregoing and other desirable objects are achieved in one preferred form of the invention as described in detail in the following specification and illustrated in the accompanying sheets of drawings in which:

Fig. 1 is a perspective view illustrating the arrangement of a semiautomatic weapon embodying shell-feeding mechanism constructed according to the present invention;

Figs. 2, 3, 4, 5 and 6 are end elevational views

showing successive stages in the cycle of operation of the shell-feeding mechanism;

Fig. 7 is a front elevational view of the lower portion of the feeding mechanism;

Fig. 8 is a similar view of the upper portion of the mechanism (Figs. 7 and 8 may be assembled, Fig. 7 below and Fig. 8 above, to afford an illustration of the complete structure);

Fig. 9 is an enlarged sectional view taken on the line 9—9 of Fig. 7 and showing in detail the construction of the energy-storing means for actuation of the feeding mechanism;

Fig. 10 is a sectional view on an enlarged scale showing the construction of part of the means for rotating the feed screws, the view being taken on the line 10—10 of Fig. 7;

Fig. 11 is a fragmentary view of a portion of the breech of the weapon and illustrating the means on the weapon which is cooperable with the feeding mechanism to impart to the latter the power generated by motion of the weapon in recoil; and

Fig. 12 is an elevation to an enlarged scale of the grooved shaft for operating the shell-feeding mechanism in response to upward or return movement of the shell tray from loading position.

For the purposes of clarity, the first portion of the description will pertain to the general construction and arrangement of the feeding mechanism and its relation to a recoiling gun. The particular type of weapon and mount chosen for the purposes of illustration comprises a mount 20 having trunnion mounts 21 each provided at its upper part with a bearing in which a respective trunnion 22 is journaled. Trunnions 22 are rigidly connected in aligned relation to opposite sides of a cradle 24 within which gun tube 32 is longitudinally slidable. A gun of this type is shown in the U. S. patent to Lucht, 2,358,340. The mechanism for controlling the gun tube in recoil and in its return to battery is contained in the annular space between the gun tube and the surrounding supporting sleeve or cradle 24. The rearward portion of the sleeve 24 is herein shown as being provided with bracket structure 25. A connection 25a between bracket structure 25 and mount 20 operates to rigidly hold the gun against elevation and depression. As was heretofore explained, the particular type of mount herein illustrated is that adapted for use in the mounting of the gun 23 in aircraft, in which instance the gun is fixed against traverse and elevation or depression. It will therefore be understood that the gun 23 may be mounted otherwise than on the mount 20, or in a manner similar to the usual mounting of artillery weapons.

The supporting sleeve or cradle 24 and rearward bracket structure 25 has supported thereon a longitudinally extending, generally cylindrical housing 26, the mounting means for the rear end of the housing being indicated as a pair of spaced brackets 26a bolted to the bracket structure 25 of the gun 23. The housing 26 carries for reciprocation therein a longitudinally extending rammer shaft 27, only the rear end portion of which is visible in the drawings. The details of the particular rammer herein illustrated are clearly brought out in my copending application, Serial No. 635,817, filed December 18, 1945, now Patent Number 2,520,966, wherein it is shown that the rammer 27 is driven rearwardly with respect to the housing 26 in response to recoil of the gun 23. The rammer remains in this rearward position while the gun returns to battery. A pivoted latch

28, controlled by a solenoid 29 mounted on the housing 26, serves as means for releasably locking the rammer in its rearward position. Also, as clearly brought out in my copending application just referred to, the rammer is returned to the position shown in Fig. 1 by means of reacting springs contained in a housing 30 formed as a coaxial extension of the housing 26. An arm 31 carried at the rear end of the rammer 27 is positionable while in its rearward position to engage a round of ammunition and, when the rammer is released by energizing the solenoid 29 to release the latch 28, the rammer arm 31 delivers or loads a round of ammunition axially into the breech of the gun 23. It will be understood that other types of ramming mechanism may be suitably employed in conjunction with the feeding mechanism to be presently described; accordingly, the presently illustrated rammer has not been set forth in greater detail.

The gun tube, herein designated as 32, projects rearwardly of the supporting sleeve 24 and is provided in the usual manner with a breech ring 33. The illustration in Fig. 11 is taken from the opposite side of the illustration shown in Fig. 1. The breech structure of the presently illustrated weapon is of the type in which the breechblock is automatically opened and closed in response to movement of the weapon out of and into battery.

The numeral 34 designates a cam member mounted at the left side of the breech ring and comprising part of mechanism, indicated generally at 35, for opening and closing the breechblock. However, the present importance of the cam member 34 lies not in its function as part of the breechblock-actuating mechanism but rather in its function as part of the means by which motion of the weapon in recoil is utilized to actuate the shell-feeding mechanism constituting the basis of the present invention.

As shown generally in Fig. 1, the feeding mechanism is a unitary structure that may be utilized in conjunction with the presently illustrated weapon or in conjunction with other weapons. The mechanism is provided with supporting structure, indicated generally at 36, which is carried at its lower portions on a longitudinally extending tubular support 37. As shown in Fig. 1, the rear end of the supporting tube 37 is mounted at the upper end of a suitable bracket or support 38 having a flanged base 39 by means of which the bracket may be secured to a supporting base or the like, herein designated at 40. This base may be the floor or other suitable component of the fuselage of an airplane or may be any other suitable mounting component in any other instance in which the feeding mechanism is utilized. The forward portion of the supporting tube 37 may likewise be suitably mounted on the floor or base 40. The supporting structure 36 includes a rigid supporting frame comprising a pair of upright members 41 and 42 each of which is preferably semicylindrical in cross section and each of which is rigidly secured at its lower end to the supporting tube 37.

As shown particularly in Figs. 1 and 8 the upright members 41 and 42 are preferably castings and are rigidly cross-connected adjacent their upper ends by intermediate frame structure 43 provided with suitable attaching flanges through which securing studs 44 are passed and threaded into the respective side portions of the uprights. The intermediate frame 43 is provided adjacent its lower portion with a depending wall structure 45 having a central vertical web sec-

tion 46 disposed in a longitudinal plane paralleling the axes of the supporting tube 37 and the bore of the gun 23. The central web is provided with a plurality of slots 47 by means of which the feeding mechanism may be additionally mounted on appropriate supporting structure in the fuselage of an airplane or in the hull of a tank, etc. Each upright 41 and 42 is provided intermediate its ends with a lower bearing 48 and at its upper end with a bearing 49. The bearings 48 and 49 of the forward upright 41 serve to carry rotatably therein a vertical feed element in the form of a feed screw or helix 50, provided at its lower and upper ends with stub shaft portions mounted respectively in the bearings 48 and 49. The rearward support 42 carries a similar feed screw or helix 51 provided at its upper end with a shaft extension 52 and at its lower end with a shaft extension 53, which shaft sections are rotatably carried respectively in the bearings 49 and 48 of the upright 42 just referred to. Because of the semi-cylindrical shape of the uprights 41 and 42, the feed screws 50 and 51 are enclosed about one-half of their peripheries, the front half of each feed screw being open to receive and carry a series of shells, as will herein-after appear in detail.

The upper shaft extension 52 (see Fig. 8) has pinned thereto for rotation therewith a bevel pinion 54 which is in constant mesh with a bevel pinion 55 carried on a longitudinal horizontal shaft 56. Each of the uprights 41 and 42 is provided with auxiliary supporting structure 57 including an appropriate bearing 58 for the proximate end of the shaft 56. Each housing 57 is provided with a suitable removable cover 59. The housing 57 at the forward upright 41 encloses bevel pinions (not shown) similar to the bevel pinions 54 and 55, by means of which the feed screw 50 may be driven by the feed screw 51. The connections are such that the feed screws rotate in opposite directions. The shaft extension 52 on the feed screw 51 extends vertically through the cover 59 on the housing 57 and has pinned, or otherwise secured thereto, at its free end means such as a crank 60 by which manual rotation of the feed screws 50 and 51 may be effected.

Referring now particularly to Figs. 1, 7, 10 and 12 the lower shaft extension 53 is provided with a spiral or helical groove or track 61, which makes one turn about the shaft. The shaft 53 is provided further with a second groove or track 62 which runs longitudinally thereof parallel to the shaft axis. The helical groove 61 begins at its lower end at an intermediate portion of the groove 62 and terminates at its upper end at a junction with the upper end of the groove 62. A sliding member 63 encircles and is carried on the shaft 53, and, as best shown in Fig. 10, is provided with a spring-pressed cam follower or detent plunger 64 which is engageable with the grooves 61 and 62 in the shaft 53. As will hereinafter appear, the member 63 is held against rotation with respect to the shaft 53. The sliding member 63 has a radially outwardly extending sleeve portion 65, which is bored to receive the plunger or follower 64 and a compression spring 66, and which is further externally threaded to receive a closure cap 67 provided with a bore through which the plunger 64 extends externally. The outer end of the plunger is provided with an operating member 68 by means of which the plunger 64 may be retracted against compression of the spring 66 and out of engagement with either groove 61 or 62. The spring 66 also serves

to maintain the plunger 64 in engagement with the grooves or tracks 61 and 62. The relationship between the shaft extension 53, with its grooves 61 and 62, and the sliding member 63, with its plunger 64, is such that axial movement of the sliding member 63 from the lower portion of the shaft 53 to the upper portion thereof effects one complete revolution of the shaft 53 and feed screws 50 and 51, whereas axial movement of the sliding member 63 downwardly on the shaft 53 does not cause rotation of the feed screws, since the plunger 64 in the sliding member 63 is following the straight groove 62.

The junction of the initiating point of the helical groove 61 with the intermediate portion of the straight groove 62 is provided with means whereby the plunger 64, upon upward movement of the sliding member 63, is forced to engage the helical groove 61 and is prevented from returning upwardly in the straight groove 62. In the present instance this means is established by a slight barrier or step 69 formed by the deeper recession of the helical groove 61. Consequently, as the plunger 64, during downward motion of the sliding member 63, is following the straight groove 62, it passes the barrier 69 and continues downwardly in the lower and more deeply recessed portion of the groove 62. Upon upward movement of the sliding member 63, the plunger 64 follows the lower portion of the straight groove 62 until the barrier or step 69 is reached. At this point the compression spring 66, maintaining constant, radially inwardly directed pressure on the plunger 64, prevents the plunger from climbing into the upper portion of the straight groove 62 and forces the plunger to follow the helical groove 61, thus effecting the desired rotation of the shaft 53 and feed screw 51, which rotation in turn causes, by means of the bevel pinions in the housing 57, reverse rotation of the feed screw 50.

As best shown in Figs. 1 and 7, the lower end of the shaft 53 of the feed screw 51 is journaled in a suitable bearing mount 70 removably secured by bolts 71 to the lower portion of the upright 42 just above the supporting tube 37.

As explained above, each upright support 41 and 42 of the supporting structure 36 is mounted at its lower end on the supporting tube 37. The rearward upright 42 is provided at the portion thereof adjacent the support 37 with a pair of longitudinally spaced, laterally extending ears 72 which carry opposite ends of a longitudinally extending pin or shaft 73. An arm 74 is mounted at its lower end for swinging movement about the axis of the pin 73. The arm 74 curves upwardly and laterally inwardly and is pivotally connected at its upper end by a pin 75 (Figs. 2-6) to the lower end of a driving link 76. The rear upright 42 is cut out, as at 42a, to accommodate movement of the arm 74. The upper end of the link 76 is bifurcated and embraces the sliding member 63. A pair of trunnions 77 provide means by which the driving link 76 is pivotally connected to the sliding member 63. Since the link 76 cannot rotate—but can pivot only on the pins 75—it serves to prevent rotation of the sliding member 63 and confines movement of the member 63 to axial movement up and down the shaft 53.

As best shown in Figs. 1 and 7, the supporting tube 37 has rockably mounted thereon means arranged for actuation by the cam member 34 on the breech ring 33 of the gun 23. This means takes the form of a shoe or cam 78 having a

pair of longitudinally spaced bearing elements 79 by means of which it is rockably mounted on the supporting tube 37. The shoe or cam 78 extends parallel to the tube 37 and is provided with a cam surface along its lower edge which extends generally horizontally forward and then inclines upwardly. As will hereinafter appear, the shoe or cam 78 is rocked about the axis of the tube 37 by the cam member 34 upon recoil of the gun.

The shoe or cam 78 includes at its rear end, 10 preferably integral therewith, an upwardly extending driving arm 80 connected by means of a pivot pin 81 to a short, laterally extending link 82. The link 82 is in turn pivotally connected by a pin 83 to a driving plunger assembly 84 mounted for reciprocation in a horizontal cylinder 85 formed in a housing 86 rigidly carried on the supporting tube 37 between the shoe or cam 78 and the rear upright support 42. As best shown in Fig. 9, the reciprocating plunger 84 comprises a sleeve 87 internally threaded at one end and receiving therein an externally threaded cap or head 88. The opposite end of the housing 86 is internally threaded and receives a plug 89 against which abuts one end of a relatively powerful driving spring 90, the other end of which is received by and abuts the cap or head 88 of the plunger assembly 84. An upper portion of the housing 86 is provided with a slot 91 disposed transversely of the axis of reciprocation of the plunger 85 and bordered by a pair of spaced ears 92. A latch 93 is pivoted on a pin 94 carried by the ears 92 and has its lower portion extending through the slot 91 and into the cylinder 85 of the housing 86. The latch 93 is formed with an upper arm 95 which extends above the ears 92 to a position in which it may be actuated by means to be described later herein for pivoting of the latch 93 so that it may be extended into or withdrawn from the cylinder 85 of the housing 86. A tension spring 96 is connected at one end between the arm 95 of the latch 93 and at its other end to a pin 97 carried by the spaced ears 92 of the housing 86. The arrangement is such that the spring 96 normally tends to pivot the latch 93 through the slot 91 so that it rests on the upper peripheral portion of the sleeve 87 of the driving plunger 84 when the spring 90 is not cocked or loaded. Thus, when the shoe or cam 78 is rocked about the tube 37, 50 the plunger 84, because of its connection with the driving arm 80 (link 82 and pins 81 and 83), is moved axially in the cylinder 85, compressing the coil spring 90. When the outer end of the plunger 84 passes the slot 91 in the housing 86, 55 the latch 93, by means of action of the spring 96, is pivoted on the pin 92 and drops behind the plunger 84, thus retaining the positions of the parts with the coil spring 90 under compression. In other words, the structure just described operates as an energy-storing means loaded by action of the gun in recoil.

The pin 75, previously described as forming the pivotal connection between the upwardly curving arm 74 and the driving link 76, extends forwardly and forms means by which the arm 74 is connected to one end of a driving link 98. As best shown in Fig. 7, the pin 83, by means of which the driving link 82 is connected to the driving plunger assembly 84, extends through the plunger 84 and projects laterally at opposite sides of the cylindrical housing 86 and, at its end opposite its connection to the link 82, is pivotally connected to the driving link 98. The pin 83 is secured in the plunger 84 by a lock pin 83a. The pin 75

housing 86 is provided with a pair of diametrically opposed slots 99 within which the pin 83 rides as the plunger assembly 84 is reciprocated in the housing.

As best shown in Figures 2 and 7, for example, each upright support 41 and 42 has rigidly secured thereto at its outer side a bearing bracket 100 (only one of which is shown). A shaft 101 is mounted at its opposite ends in the brackets 100 and a sleeve 102 is rotatably carried on the shaft 101. The shaft 101 and sleeve 102 serve to mount shell-delivery means on the supporting structure 36 in a manner to cooperate with the feed screws 50 and 51 in delivering shells to a position from which such shells may be loaded by the rammer 27-31 into the breech of the gun 23. In the present instance the shell-delivery means takes the form of a tray, designated generally by the numeral 103, comprising a pair of arms 104 secured in longitudinally spaced apart relation to the sleeve 102. As best shown in Fig. 2 for example, each arm 104 is formed generally as a reverse S, the free end of which includes a cradle portion 105. The arms 104 are rigidly connected across the cradle portions thereof by a pair of parallel supporting strips 106. The supporting strips 106 extend at their forward ends to a point generally in alignment with the forward edge of the forward upright support 41. The rearward ends of the supporting strips extend rearwardly beyond the rearward upright support 42 and generally in alignment with a vertical, grooved guiding strip 107 which is supported at its upper and lower ends by brackets 108 and 109, respectively, rigidly secured to the rearward side of the rear support 42. The upper bracket includes an outwardly and downwardly curved supporting arm 110 which carries at its free end one end of a longitudinally extending rod 111, the other end of which is supported in the free end of a similar curved arm 112 rigidly mounted on the front upright 41 by means of an extension support 113. The lower bracket 109 includes an outwardly and upwardly curved supporting arm 114 which carries the free end of a longitudinally extending rod 115. A lower extension support 116 is rigidly carried by the forward side of the forward upright 41 and includes an outwardly and upwardly curved supporting arm 117 on the free end of which the forward end of the rod 115 is mounted. The mounting of the rods 111 and 115 is such that they are disposed outwardly of the feed screws 50 and 51 a distance substantially equal to the caliber of the ammunition for which the feeding mechanism is adapted. A pair of vertical guide members 118, rigidly carried by the supporting rods 111 and 115, completes the guide structure which cooperates with the feed screws 50 and 51 in the feeding of shells to the tray 103.

As best shown in Figs. 2 and 8, for example, the configuration of each feed screw is such that the continuous spiral forming the helix thereof provides a plurality of vertically spaced pockets shaped to receive and engage a plurality or series of horizontally disposed rounds of ammunition such as shells 119. The shells or rounds herein illustrated are of usual design and include a projectile 120 and shell case 121. Each shell case includes at its base a rim 122, as is conventional. As best shown in Figs. 1 and 8, the guide strip 107 is provided with a groove which receives and guides the inner portions of the shells 119, thus preventing the shells from endwise displacement. As shown in Fig. 2, for example, the location of the vertical guide members 118 is such as to con-

fine the shells or rounds 119 to the feed screws 50 and 51. It will be noted also that the upper end of each guide member 118 curves upwardly and outwardly so that the space between the guides 118 and feed screws 50 and 51 is enlarged, thus permitting the loading of shells into the feed mechanism. It will also be noted that the upper and lower extension supports 113 and 116 provide for the disposition of the supporting arms 112 and 117 sufficiently far forwardly on the supporting structure 36 to clear the noses of the projectiles 120. Each of the longitudinally extending supporting strips 106 on the tray 103 is provided at its rearward end with a retaining clip 123 (Figure 8) which, in addition to the grooved guide strip 107, cooperates with the rims 122 of the shells 119 to prevent endwise displacement of the shells while in position in the feed-supporting structure 36. The clips 123 serve by themselves to retain a shell against endwise displacement rearwardly when such shell is carried by the tray 103.

As best shown in Fig. 7, the driving link 98 is spaced on the connecting pin 75 from the arm 14 and the pin 75 receives in this space the lower end of an upwardly extending link 124, the upper end of which is pivotally connected by a pin 125 to the rearward arm 104 of the tray 103. The link 98, forming the connection between the pin 83 and the links 76 and 124, is provided with a pair of longitudinal slots 126 and 127 which cooperate respectively with the pins 75 and 83 to provide for necessary lost motion as the driving spring 90 is compressed in the housing 86 by the plunger 84. The details of the functioning of the link 98 in this respect will be clearly brought out in the description of the operation of the mechanism.

The connecting pin 125, by means of which the link 124 is connected to the rear arm 104 of the tray 103, is formed with an extension at the inner side of the arm 104 on which is pivotally mounted a shell-retaining element designated generally by the numeral 128. The other arm 104 of the tray 103 is provided with a pivot pin 129 on which is mounted a similar shell-retaining element 130. Each shell-retaining element is in the form of a bell crank fulcrumed or pivoted on the pivot pin 125 (129) and has an actuating arm 131 and a retaining arm 132. As best shown in Fig. 2, the normal position of each shell-retaining element is such that the retaining arm 132 thereof lies alongside the shell that is in the tray 103. The retaining arms 132 are respectively provided with rollers 133 rotatable respectively on the axis of the retaining arms and engageable with the periphery of a shell in the tray. Each retaining element is formed at its fulcrum with a depending ear 134 to which is connected one end of a tension spring 135, the other end of which is connected by a pin 136 to the arm 104 of the tray 103. The function of the springs 135 is to resiliently maintain the rollers 133 on the retaining arms 132 in engagement with the shell in the tray.

When the tray is carrying a shell, the normal position of the actuating arms 131 is such that these arms lie alongside the intermediate portion of the tray arms 104. It is an important feature of the present invention to provide means for maintaining the shell-retaining elements positively in engagement with the shell in the tray as the tray swings on its pivot 101 from the position shown in Fig. 2 to the position shown in Fig. 5, and to incorporate in this means, mechanism for retracting or opening the shell-retaining ele-

ments when the empty tray returns to its starting position (Fig. 2). As best shown in Fig. 7, the intermediate connecting structure 45, between the upright supports 41 and 42, includes a lower horizontal mounting pad 137 to which is rigidly secured a depending bracket 138 having longitudinally spaced sidewall portions in which is mounted a longitudinally extending shaft 139. The shaft 139 has pivotally mounted thereon a pair of downwardly and laterally extending actuating plates 140. Torsion springs 141 are carried on the shaft 139 and are respectively engageable between the plates 140 and the bracket 138 and serve as means for resiliently urging the plates 140 upwardly against a stop pin 142 extending longitudinally between the depending sidewall portions of the bracket 138 (Fig. 2). Each plate 140 is provided with an offset guide portion 143 cooperable with rollers 144, respectively, on the actuating arms 131 of the shell-retaining elements 128 and 130. As will be hereinafter more fully explained in detail, the guide portions 143 of the guiding plates 140 respectively engage the rollers 144 of the shell-retaining elements 128 and 130 during upward and downward swinging of the tray 103. As the tray moves downwardly, the rollers 144 ride on the upper surfaces of the guide portions 143 (Fig. 4) until the tray reaches its lowermost position wherein the shell is aligned with the chamber or breech of the gun 23. During upward movement of the tray, the rollers 144 engage the under surfaces of the guide portions 143 (Fig. 6), thus causing retraction or opening of the retaining elements 128 and 130 so that the cradle portion 105 of the tray may receive another shell from the feed screws 50 and 51. As indicated in Figs. 1 and 7, the upper and lower surfaces of the guide portions 143 of the plates 140 may be provided with wear strips.

As previously stated, the movement of the tray 103 during the loading and firing cycles is between the position shown in Fig. 2 and the position shown in Fig. 5. It will be noted that the tray 103 consequently swings from a shell-receiving position (Fig. 2), above and to one side of the extended axis of the bore of the gun 23, to a shell-delivery position (Fig. 5) in which the tray supports the shell substantially in axial alignment with the bore of the gun. It will be further noted, however, that movement of the tray must be so timed with respect to recoiling of the gun that the tray will be out of the path of the recoiling parts of the gun. Consequently, it is desired that the tray be in shell-receiving position (Fig. 2) when the weapon recoils. For this purpose, there is provided, according to the present invention, means for controlling the positioning or movement of the shell tray 103.

Each tray arm 104 is provided with a bearing portion 145 provided with a square opening 146. The openings 146 are longitudinally aligned and carry for reciprocation therein a longitudinally extending release or actuating bar 147, which is square in cross section. Adjacent the rearward tray arm 104 the actuating bar 147 has rigidly secured thereto a depending arm 148, the function of which will appear shortly. The release bar 147 has rigidly secured thereon, adjacent the forward tray arm 104, a flanged collar 149. The forward tray arm 104 is provided, just below the collar 149, with a pair of spaced mounting ears 150. A pin 151 is carried by the ears and in turn serves to pivotally mount a swinging lever 152, having its upper arm formed as a yoke fitting the collar 149, and having its lower arm pivotally

connected to a spring-pressed plunger 153 carried in a bore in a boss 154 on the forward tray arm 104.

The sleeve 102 on the tray-mounting shaft 101 is provided between the tray arms 104 with a support or bracket 155 on which is mounted means for actuating the release bar 147. This means may take any suitable form and is herein indicated as an electrically-energizable solenoid 156 having its plunger 157 arranged to extend and depress the plunger 153, causing rocking of the lever 152 about its pivot 151 and driving the release bar 147 rearwardly (or to the left as viewed in Fig. 7). The forward upright support 41 carries at its inner or rear side a generally triangular shaped bracket 158 having a rearwardly directed portion on which is provided a lug 159. At its extreme inner edge the bracket 158 is provided with a stop 160 against which the proximate tray arm 104 abuts when the tray is in upper or shell-receiving position (Figures 2 and 3). The lower or front portion of the bracket 158 is provided with a similar stop 161 which limits downward movement of the tray 103. The bracket 158 includes a second lug 162 adjacent its lower portion just above the stop 161.

In the operation of the feeding mechanism in conjunction with an automatic weapon of the type herein referred to, the shell-carrying means, comprising the feed screws 50 and 51 and the guide structure 107-118, is loaded with a plurality or series of shells or rounds 119. As previously described, the loading operation is performed manually by insertion of individual shells at the upper end of the shell-retaining means—at the portion thereof provided by the curved upper ends of the vertical guide members 118. As each shell is loaded into the carrying means, the crank 60 is rotated so that the shell is advanced downwardly until the feed screws are completely filled with shells. In the present instance, the shell-carrying means is capable of holding a series of five rounds. It will be assumed that the gun has been loaded manually with a first round and is ready for firing. The tray 103 is in its upper or shell-delivery position (Fig. 2), in which position it is maintained by means of the engagement between the release bar 147 and lug 159 on the triangular bracket 158. The spring 90, in the cylinder housing 86, will be uncompressed and the driving plunger 84 will be at its extreme endmost or outer position. The shoe or cam 78 will be in the position shown in Figs. 1 and 2, in which position it will be engaged for rocking on the tube 37 by the cam member 34 upon recoil of the gun 23. The rammer 27 will be in its forwardmost position, in which it is normally resiliently maintained by means of the springs previously referred to as being enclosed in the housing 30 at the forward end of the rammer housing or support 26. After the weapon is fired, and the tube and breech recoil, the cam member 34, on the left side of the breech ring 33 (Fig. 11), will engage the under cam surface of the shoe or cam 78 and will rock the shoe 78 about the longitudinal axis of the supporting tube 37.

As the shoe 78 is rocked, the driving plunger 84, through the arm 80 and link 82, is moved inwardly in the cylinder housing 86 to a point where it completely compresses the driving spring 90, whereupon the latch 93, under tension of the spring 96, drops in behind the driving plunger 84 and locks the plunger in position with the spring 90 loaded or cocked for reaction. Dur-

ing this phase of the operation, no change occurs in the positions of the tray 103 or any of the components of the shell-carrying means (feed screws 50-51 and guide structure 107-118) or in the positions of the control mechanism therefor (147-159). However, the driving arm 80 on the shoe or cam 78 is swung in a counterclockwise direction from its position as shown in Fig. 2 to its second position as shown in Fig. 3. Since there are no changes in the positions of the arm 74 and links 76 and 124, there must necessarily be provision for lost motion in the linkage between these parts and the arm 80. As previously stated, this lost motion is accommodated by provision of the slots 126 and 127 in the link 98 which cooperate with the pins 75 and 83, respectively, to permit the link 98 to assume the upright position shown in Fig. 3. Since the tray 103 remains in its shell-receiving position (Figs. 2 and 3), it is out of the path of the recoiling breech and is likewise out of the path of the rearwardly moving rammer arm 31, which, as previously referred to, is driven rearwardly upon recoil of the gun.

After the gun is fired and recoils, it returns to battery, but the rammer remains in rearward position because of operation of the latch 28 and is just rearwardly of the rear of the tray 103, so that when the tray moves to shell-delivery position, the shell therein may be engaged by the rammer arm. When the rammer is in rearward position the inner end of the rammer arm is substantially in axial alignment with the bore of the chamber of the gun. The release solenoid 156 is under control of the operator and is preferably energizable through a suitable electrical circuit (not shown), although any other appropriate control system may be employed. When the solenoid 156 is energized, its plunger 157 is driven outwardly or forwardly into engagement with the lower lever of the lever arm 152, with the result that the release bar 147 is moved rearwardly, thus releasing its forward end from engagement with the lug 159 on the triangular bracket 158. The lowermost shell 119 in the vertical series of shells in the shell-carrying means is already received by the tray 103 and is retained therein by means of the shell-retaining bell cranks 128 and 130. The weight of the loaded tray is sufficient, after release of the bar 147 from the lug 159, to effect movement of the tray by gravity from its position in Figs. 2 and 3, through the phase of movement illustrated in Fig. 4, to the position illustrated in Fig. 5. During downward travel of the loaded tray 103, the rollers 144 on the shell-retaining bell cranks 128 and 130 ride on the upper surfaces of the guide portions 143 of the guide plates 140. Since the path of travel of the axis of the rollers 144 is arcuate about the axis of shaft 101 as a center as the tray swings from the shell-receiving position to shell-delivery position (Fig. 2 to Fig. 5), the rollers depress the guide plates 140 against the relatively light tension of the torsion springs 141. It will be noted that the guide plates 140 are independently mounted on the supporting rod 139 to allow for variations in the positions of the shell-retaining bell cranks 128 and 130 caused by varying contours of different type shells.

As the tray approaches the position assumed in Fig. 5, the rollers 144 run off the end of the upper surfaces of the guides 143 (Fig. 4). However, the retaining bell cranks 128 and 130 are maintained in engagement with the shell by action of the springs 135. When the shell is

rammed from the tray 103 into the breech of the gun, the bell cranks 128 and 130 may yield in response to variations in the contour of the shell as the shell passes the rollers on its way to the breech. It is particularly desirable that the rollers 144 yield as the rim 122 of the shell passes.

As the loaded tray 103 progresses from the position shown in Fig. 2 to the position shown in Fig. 5, there will be no change in the position of the shoe or cam 78, the driving arm 80 or the driving plunger 84, since the latch 93 has locked the plunger 84 in position with the coil spring 90 cocked or under compression. When the loaded tray 103 reaches the position shown in Fig. 5, the release bar 147, which after release from the lug 159 has returned to fully extended position to the right because of breaking of the circuit to the solenoid 156 and reaction of the spring-pressed plunger 153, rides over the lug 162 on the bracket 158 and the end portion thereof snaps back to engage that lug. This action of the parts effects a lock that releasably retains the loaded tray in shell-delivery position. Consequently, there can be no accidental bouncing of the tray as the shell is cleared therefrom by the rammer.

With the tray in the position shown in Fig. 5, the release bar 147 engages the lug 162 as aforesaid, and in addition the release arm 148 is aligned with the upper arm 95 of the release latch 93 on the housing 86. With the parts in this position, the shell in the tray is now ready to be rammed into the breech or chamber of the gun. The control means for the rammer solenoid 29 is actuated to energize the solenoid 29 to effect release of the latch 28, thus permitting the rammer to be driven forwardly, carrying with it the shell from the tray 103. In the preferred type of automatic weapon and control therefor, as disclosed in my copending application, Serial No. 635,818, filed December 18, 1945, referred to above, an electric circuit is provided and is controlled by switches actuated by the rammer when it reaches its forward position. These switches complete the circuit to the tray-release solenoid 156, which when energized again, drives its plunger 157 against the lever 152 and causes rearward movement of the release bar 147 and release arm 149. This movement causes the release arm 148 to engage the upper arm 95 of the latch 93 on the cylinder housing 86 and withdraws the latch from its position behind the driving plunger 84 against the urge of spring 96. Reaction of the now released compression spring 96 serves to drive the driving arm 80 in a clockwise direction and operates through the link 98 to swing the arm 74 also in a clockwise direction about its pivot 73. This movement of the arm carries with it the lower ends of the links 76 and 124, which action results in upward movement of the tray 103 (Fig. 6) to the starting position shown in Fig. 2. It will be noted from Fig. 5 that after the energy-storing means 84-90 has been loaded for reaction, the relation between the driving link 80 and the connecting pins 75 and 83 is such that these pins are at the far ends of the slots 126 and 127 and there is therefore no lost motion in the return movement of the parts from the position shown in Fig. 5 to the position shown in Fig. 2.

During the movement of the tray from the shell-receiving position shown in Fig. 2 to the shell-delivery position shown in Fig. 5, there is no rotation of the feed screws 50 and 51, since the plunger 64 on the sliding member 63, in its movement down the shaft 53, follows the straight groove 62. Consequently, the series of shells 119

will not be advanced and the lower portions of the feed screws 50 and 51 will be vacant. When the solenoid 156 is energized to effect actuation of the release bar 147 and release arm 148 for the release of the spring-loaded plunger 84 for reaction, the link 76 drives the sliding member 63 upwardly on the shaft 53. During this phase of the movement of the sliding member 63, the plunger 64 thereof rides the groove 61 in the shaft 53, thus imparting one revolution to the feed screw 51, which motion is in turn imparted to the feed screw 50 in the manner previously described. As stated above, the plunger 64 of the sliding member 63 necessarily follows the spiral groove 61 in the shaft 53 because of the relationship between the grooves 61 and 62 at their lower junction; that is to say, the barrier 69 formed by the deeper recession of the spiral groove 61 prevents the plunger 64 in the sliding member 63 from continuing upwardly in the groove 62. The feed screws 50 and 51 rotate toward each other so that any tendency to impart translational or longitudinal shifting of a shell by either feed screw will be neutralized by the other feed screw and the single revolution of each advances the series of shells carried by the feed screws so that the next lowermost shell is advanced to a position from which it will be delivered to or received by the tray 103 as the tray returns to shell-receiving position (Fig. 5).

As shown in Fig. 6, and as previously referred to generally, the rollers 144 on the shell-retaining bell cranks 128 and 130 engage the under surfaces of the guide portions 143 on the guide plates 140, thus causing the shell-retaining bell cranks to open. It will be noted that the length of each guide portion 143 is such that the shell-retaining bell cranks are kept in open position until the tray 103 moves completely to shell-receiving position (Fig. 2), at which time the rollers 144 ride past the inner ends of the guide portions 143 and permit the shell-retaining bell cranks to close on the shell that has previously been advanced to shell-delivery position.

When the tray reaches the position shown in Fig. 2, the release bar 147 again engages the upper lug 159 on the bracket 158 and the tray is locked in that position until the next feeding cycle is initiated. The synchronous rotation of feed screws 50 and 51, in response to upward movement of sleeve 63, feeds the shells downwardly and releases the lowermost shell to tray 103 at substantially the instant the tray moves into and is locked in the uppermost position of Figure 2.

The foregoing description pertains to the operation of a feeding mechanism that has been made as simple and as effective as possible, with due consideration given to military requirements. As has been stated, downward movement of the tray 103 is effected by release of the release bar 147 from the upper locking lug 159, after which the tray depends upon the weight of itself and of the shell carried thereby to move completely to the position shown in Fig. 5. In certain circumstances it may be desirable to assist downward movement of the tray 103 by spring means, for example, or some other means positively driving the tray downwardly. It is contemplated that this change can be effected within the scope of the present invention. Likewise, numerous other modifications and alterations may be made in the preferred form of the invention without departing from the spirit and scope thereof as defined in the appended claims.

I claim:

1. Shell-feeding mechanism for a gun having a tube-and-breech assembly mounted for recoil, comprising a support positioned rearwardly and to one side of the gun, means on said support at a level above the extended axis of the tube-and-breech assembly for carrying a series of shells one above the other with their axes generally horizontal, a shell tray, means mounting said tray on said support rearwardly of the gun for movement from an upper position adjacent said shell-carrying means to receive the lowermost shell from said series to a lower shell-delivery position generally aligned axially with the tube-and-breech assembly, means operable to move said tray upwardly relatively to said shell-carrying means to shell-receiving position, driving means powered by the recoil of the tube-and-breech assembly for actuating said tray-moving means, means responsive to upward movement of said tray for actuating said shell-carrying means to release the lowermost shell of said series onto said tray and simultaneously positively advancing said series of shells to position the next shell in position to be released, means for releasably holding said tray in its shell-loading position, said shell carrying means acting to retain said series of shells while said tray is moving to said lower position and means operable to simultaneously release said driving means and said tray holding means.

2. Shell-feeding mechanism for a gun having a tube-and-breech assembly mounted for recoil, comprising a support positioned rearwardly and to one side of the gun, means on said support at a level above the extended axis of the tube-and-breech assembly for carrying a series of shells one above the other, a shell tray, means mounting said tray on said support rearwardly of the gun for movement from an upper position adjacent said shell-carrying means to receive a shell from said series to a lower shell-delivery position generally aligned axially with the tube-and-breech assembly and remote from said shell-carrying means, driving means powered by the recoil of the tube-and-breech assembly and operable to actuate said tray-moving means upwardly to shell receiving position, means operated in response to movement of said tray upwardly to actuate said shell-carrying means and thereby deposit a shell from said series into said tray and simultaneously advance said series of shells to position another shell in position for loading onto said tray, and manually-controlled means operable to releasably lock said tray in shell-receiving position, said last named means when operated to release said tray also releasing said driving means.

3. Shell-feeding mechanism for a recoiling gun, mounted for movement in recoil and counterrecoil, comprising a support, means on said support for carrying a series of shells, a shell tray, means mounting said tray on said support for pivotal movement on an axis parallel with the bore of said gun from a position adjacent said series of shells to receive a shell therefrom to a position substantially coaxial with the bore of said gun, energy-storing means on said support, means connecting said energy-storing means to said tray for moving said tray to shell-receiving position, means powered by recoil of the gun to energize said energy-storing means, means for releasably locking said energy-storing means after energizing thereof, means for re-

leasing said locking means to effect movement of said tray to shell-receiving position by said energy-storing means, means for depositing a shell from said series onto said tray in response to movement of said tray to shell-receiving position, means connected to and powered by said energy-storing means for advancing another shell to discharge position, and manually controllable means for releasably locking said tray and shell received thereby in shell-receiving position.

4. Shell-feeding mechanism for a gun mounted for reciprocation in recoil and counterrecoil, comprising a support, means on said support for carrying a series of shells, a shell tray, means mounting said tray on said support for movement from a position adjacent said series of shells to receive a shell therefrom to a position for loading said shell into said gun by axial movement of said shell, energy-storing means on said support, means connecting said energy-storing means to said tray for moving said tray to shell-receiving position, means driven in response to recoil of the gun to energize said energy-storing means, means releasably locking said energy-storing means after energization thereof, means movable as a unit with said shell tray and effective only when said tray is in shell-loading position for releasing said locking means to permit movement of said tray to shell-receiving position by reaction of said energy-storing means, means responsive to movement of said energy-storing means for operating said shell-carrying means, to thereby deposit a shell from said series into said tray as said tray moves into shell-receiving position, and means for releasably locking said tray and shell received thereby in shell-receiving position.

5. Shell-feeding mechanism for a gun mounted for reciprocation in recoil and counterrecoil, comprising a support, means on said support for carrying a series of shells in horizontal superposed relation, a shell tray, means mounting said tray on said support for vertical oscillatory movement from an upper position adjacent said series of shells to receive the lowermost of said shells to a lower shell-delivery position where said shell may be loaded into said gun by axial translation, spring means on said support, means connecting said spring means to said tray for moving said tray upwardly from shell-delivery position to shell-receiving position, means powered by recoil of the gun to load said spring means, means for releasably locking said spring means after loading thereof, means carried by said tray and operable only when the same is in shell-delivery position for releasing said locking means to effect movement of said tray upwardly to shell-receiving position by reaction of said spring means, and means operated in response to movement of said tray to shell-receiving position for driving said shell-carrying means to thereby deposit a shell from said series into said tray upon movement of said tray.

6. Shell-feeding mechanism for a gun having a breech, comprising a support, means on said support at a level above the axis of said breech for carrying a series of shells one above the other with their axes generally horizontal, a shell tray, means mounting said tray on said support for vertical movement on a pivot axis parallel with the bore of said gun, from an upper position to receive the lowermost shell from said series of shells to a lower position from which a shell may be delivered axially to the

breech of the gun, spring means for moving said tray upwardly to shell-receiving position, feed screw means for retaining said lowermost shell while said tray is moving to and in shell-delivery position, said feed screw means being operated in response to movement of said tray to shell-receiving position to deposit said lowermost shell into said tray, and means operable only when said tray is in shell-loading position for releasing said spring means.

7. Shell-feeding mechanism for a gun mounted for reciprocation in recoil and counterrecoil, comprising a support, means on said support at a level above the axis of the breech of said gun for carrying a series of shells one above the other with their axes generally horizontal, a shell tray, means mounting said tray on said support for vertical movement about an axis parallel with the bore of said gun, from an upper position to receive the lowermost shell from said series of shells to a lower position from which a shell may be delivered axially to the breech of the gun, spring means for moving said tray upwardly to shell-receiving position, said shell-carrying means acting to retain said shells immovable while said tray is in shell-delivery position, means responsive to movement of said tray-moving means to shell-receiving position to operate said shell-carrying means to deposit said lowermost shell into said tray, releasable means for locking said tray in shell-receiving position, and means for releasing said releasable means so that said tray and shell may move by gravity to shell-delivery position.

8. In a shell-feeding mechanism for a gun, a support, feed screw means on said support for carrying a series of shells in position laterally spaced from said gun, a shell tray mounted on said support for movement from a first position adjacent said shells to receive a shell therefrom, to a second position in which a shell thereon may be rammed into said gun, power means operable to move said tray from said second to said first position and simultaneously operate said feed screw means, to deposit a shell in said tray as the tray arrives at said first position, and means carried by said support and tray and operable only when said tray is in said second position for rendering said power means operable.

9. Shell-feeding mechanism for a gun, comprising a support, means on said support for carrying a series of shells, a shell tray, means mounting said tray on said support for movement from a shell-receiving position adjacent said series of shells to a shell-delivery position remote from said series of shells, energy-storing means on said support, means for loading said energy-storing means, first releasable locking means on said support for locking said energy-storing means upon loading thereof, second releasable locking means on said support for locking said tray in shell-receiving position, means for releasing said second locking means to permit gravitational movement of said tray and shell received thereby to shell-delivery position, said means for releasing being operable to release said energy-storing means when said tray is in shell-delivery position only, and means driven by said energy-storing means when released, to return said tray to shell-receiving position.

10. In a shell-feeding mechanism for an automatic gun, a support, means on said support to carry a plurality of shells and to progressively move the same to a shell-depositing position re-

mote from the gun, a shell tray, means pivoting said tray on said support for movement from a first position to receive a shell at said shell-depositing position, to a second or shell-loading position, energy-storing means on said support, means responsive to recoil of the gun for loading said energy-storing means, latch means on said support for releasably locking said energy-storing means when loaded, locking means carried by said tray to releasably lock the same in either said first or second position, said locking means being operable when said tray is in second position only to operate said latch means and release said energy-storing means, and means driven by said energy-storing means to move said tray from second to first position.

11. Shell-feeding mechanism for a gun, comprising a support, means on said support for carrying a series of shells, a shell tray, means mounting said tray on said support for movement from a shell-receiving position adjacent said series of shells to a shell delivery position remote from said series of shells, energy-storing means on said support, means for loading said energy-storing means, first releasable locking means on said support for locking said energy-storing means upon loading thereof, second releasable locking means on said support for locking said tray in shell-receiving position, means on said tray cooperable with said second locking means when said tray is in shell-receiving position for releasing said tray to permit gravitational movement thereof to shell-delivery position and cooperable with said first locking means when said tray is in shell-delivery position for releasing said energy-storing means for reaction, and means connected to said tray and operable to move said tray to shell-receiving position and simultaneously to actuate said shell-carrying means to advance another shell to position to be received by said tray.

12. Shell-feeding mechanism for a gun, comprising a support, means on said support for carrying a series of shells, a shell tray, means mounting said tray on said support for movement from a shell-receiving position adjacent said series of shells to a shell-delivery position remote from said series of shells, driving means on said support for moving said tray to shell-receiving position, releasable locking means on said support for locking said tray in shell-receiving position, means on said tray cooperable with said locking means when said tray is in shell-receiving position for releasing said tray to permit gravitational movement of said tray to shell-delivery position, said last-named means being operable when said tray is in shell-delivery position only to activate said driving means to return said tray to shell-receiving position.

13. Shell-feeding mechanism for a gun, comprising a support, a pair of parallel, rotatable screw members for carrying a series of shells transversely thereon, a shell tray, means mounting said tray on said support for movement from a shell-receiving position adjacent said screw members to receive a shell therefrom to a shell-delivery position remote from said screw members, means for moving said tray, a drive shaft formed with a helix, means connecting said shaft to one of said screw members for rotation thereof, drive means movable axially on said shaft and engageable with the helix thereon, means connecting said drive means and said tray for moving said drive means to rotate said shaft upon movement of said tray to shell-receiving posi-

tion, and means connecting said screw members for rotation together.

14. Shell-feeding mechanism for a gun, comprising a support, a rotatable screw member for carrying a series of shells transversely thereon, a shell tray, means mounting said tray on said support for movement from a shell-receiving position adjacent said screw member to receive a shell therefrom to a shell-delivery position remote from said screw member, means for moving said tray, a drive shaft formed with a helix, means connecting said shaft to said screw member for rotation thereof, drive means movable axially on said shaft and engageable with the helix thereon, and means connecting said drive means and said tray for moving said drive means to rotate said shaft upon movement of said tray to shell-receiving position.

15. Shell-feeding mechanism for a gun having a recoiling tube-and-breech assembly, comprising a support, means for carrying a series of shells at a level above and spaced transversely to one side of the extended axis of the tube-and-breech assembly, means on said support and connected to said shell-carrying means for feeding shells successively downwardly, tray means movable transversely on said support from a first position adjacent said shell-carrying means to a second position rearwardly of and generally in axial alignment with the tube-and-breech assembly for conveying shells successively from said shell-carrying means into position for loading into the gun, means powered by recoil of the tube-and-breech assembly for driving said tray means to first position, and a driving connection between said shell-carrying means and said tray means for driving said shell-carrying means to feed a shell to said tray means simultaneously with movement thereof to first position.

16. Shell-feeding mechanism for a gun having a recoiling tube-and-breech assembly, comprising a support, means on said support including a pair of vertical reversely rotatable parallel feed screws for carrying a series of shells horizontally one above the other, a drive shaft journaled on said support, means connecting said shaft to said screws, a drive member rockable on said support and arranged to be rocked by recoil of the gun, and drive means connected between said rockable member and said drive shaft.

17. Shell-feeding mechanism for a gun having a recoiling tube-and-breech assembly, comprising a support, means on said support including a pair of vertical reversely rotatable parallel feed screws for carrying a series of shells horizontally one above the other, a drive shaft journaled on said support, means connecting said shaft to said screws, a cam member rockably mounted on said support and arranged to be actuated by the recoiling tube-and-breech assembly of the gun, a shell tray, means mounting said tray on said support for movement from a shell-receiving position adjacent said feed screws to a shell-delivery position adjacent the tube-and-breech assembly, energy-storing means on said support, means connected between said energy-storing means and said cam member to load said energy-storing means upon rocking of said cam member, releasable means for locking said energy-storing means when loaded, drive means connected between said tray and said drive shaft, and means for releasing said locking means for reaction to move said tray to its shell-receiving position and consequently to drive said drive shaft and rotate said feed screws for advancing the series of shells carried by said feed screws.

advancing the series of shells carried by said feed screws.

18. Shell-feeding mechanism for a gun having a recoiling tube-and-breech assembly, comprising a support, means on said support including a pair of vertical, reversely rotatable parallel feed screws for carrying a series of shells in side-by-side relationship transversely thereof, a drive shaft journaled on said support, means connecting said shaft to said screws, a drive member rockable on said support and arranged to be rocked by recoil of the gun, and drive means connected between said rockable member and said drive shaft.

19. Shell-feeding mechanism for a gun having a recoiling tube-and-breech assembly, comprising a support, means on said support including a pair of reversely rotatable parallel feed screws for carrying a series of shells in side-by-side relationship transversely thereof, a drive shaft journaled on said support, means connecting said shaft to said screws to rotate the same, a cam member rockably mounted on said support and arranged to be actuated by the recoiling tube-and-breech assembly of the gun, a shell tray, means mounting said tray on said support for movement from a shell-receiving position adjacent the delivery ends of said feed screws to a shell-delivery position adjacent the tube-and-breech assembly, energy-storing means on said support, means connected between said energy-storing means and said cam member to load said energy-storing means upon rocking of said cam member, releasable means for locking said energy-storing means when loaded, drive means connected between said energy-storing means, said tray and said drive shaft, and means operable only in shell-delivery position of said tray, for releasing said locking means for releasing said energy-storing means for reaction to move said tray to its shell-receiving position and consequently to drive said drive shaft and rotate said feed screws for advancing the series of shells carried by said feed screws.

20. In a shell-feeding mechanism, a support, feed means including a pair of spaced, parallel feed screws rotatably carried by said support, said screws being formed to carry a series of shells arranged in side-by-side relationship with their axes normal to said feed screws, means connecting said feed screws for synchronous rotation to advance the shells downwardly for release at one end of said feed screws, means for rotating said feed screws, and means carried by said support and cooperable with said feed screws to retain and guide the shells therealong in stacked, side-by-side relation, said means being formed in the vicinity of the release end of said feed means with guide means for the release of shells from said feed screws.

21. In a shell-feeding mechanism, a generally vertical supporting structure, a pair of transversely spaced, parallel, vertical feed screws rotatably carried by said support, said screws being formed to carry a series of shells arranged horizontally one above the other in side-by-side relationship with their axes normal to said feed screws, means connecting said feed screws for synchronous rotation in opposite directions to advance the shells downwardly for release at the lower ends of said feed screws, means for rotating said feed screws, and means carried by said support and cooperable with said feed screws to retain and guide the shells, said means being formed in the vicinity of the lower ends of said feed screws.

- feed screws to release shells from said feed screws.
22. In a shell-feeding device for a gun, a support, first means on said support for carrying a plurality of shells and for feeding the same successively to a first position for release therefrom, a shell-carrying tray movable from said first position to a second position in which a shell thereon may be rammed into the gun, a guide plate pivoted on said support, a lever pivoted on said tray and having a first shell-engaging arm and a second plate-engaging arm, said second arm engaging one side of said plate to urge said first arm into position engaging and holding a shell in said tray as said tray moves from first to second position, said second arm engaging the other side of said plate to hold said first arm out of shell-engaging position whereby a shell may be deposited on said tray as said tray moves from second to first position and means responsive to movement of said tray from second to first position to operate said first means to deposit a shell in said tray as the latter moves into first position.
23. In a shell-feeding mechanism for an automatic gun, a support, means on said support for carrying a plurality of shells and for feeding the same in succession to a first position for release therefrom, a shell tray, means pivoting said shell tray on said support on a first axis for movement from said first position to a second position where a shell thereon may be rammed into the gun, a guide plate pivoted on said support on a second axis in the plane of said plate and parallel with said first axis, a bellcrank pivoted on said tray and having a first shell-engaging arm and a second plate-engaging arm, spring means urging said bellcrank into position where said first arm engages and holds a shell on said tray, said plate and second arm cooperating to move said first arm out of shell-engaging position as said tray moves from second to first position.
24. In a shell-feeding mechanism for a gun mounted for recoil and counterrecoil, means including a pair of parallel feed screws for carrying and simultaneously moving a series of shells in parallel stacked relation, a shell tray pivotable on an axis parallel with the bore of said gun from a first position to receive the lowermost shell of said series, to a second position in which said shell is aligned with the barrel of said gun, means for maintaining a shell in said tray while said tray is moving from said first position to said second position, said means comprising a bellcrank pivoted on said tray and having a first arm adapted to engage a shell in said tray and a plate yielding mounted adjacent and engaged by the second arm of said bellcrank to urge said first arm into engagement with a shell in said tray while the tray is moving from said first to said second position, said second arm engaging the other side of said plate to maintain said first arm in open position while said tray is moving from said second to said first position.
25. In a shell-feeding device for a gun, a tube, means fixedly mounting said tube parallel with the gun rearwardly and laterally thereof, a frame

- upstanding from said tube and fixedly carried thereby, a pair of spaced parallel vertical feed screws journaled in said frame, means connecting said screws for synchronous rotation, means co-operating with said screws to hold a series of shells within the convolutions thereof in spaced parallel superposed relation, a shaft connected for synchronous rotation with said feed screws, there being a spiral groove in and extending through 360° about said shaft and a straight longitudinal groove connecting the ends of the spiral groove, a slide mounted for translation only on and along said shaft, a rider carried by said slide and adapted to traverse said grooves as said slide reciprocates on said shaft in opposite directions, respectively, a shell tray mounted in said frame for pivotal movement about an axis parallel with said tube from a first shell-receiving position adjacent the lower end of said screws to receive a shell therefrom, to a second shell-loading position wherein a shell carried thereby is positioned for ramming into the breech of the gun, spring driving mechanism, means adapted to be operated by recoil of the gun to energize the spring of said driving mechanism, a spring latch carried by said driving mechanism and automatically operable to hold the spring thereof in energized position, means including a release rod slidable on said tray for releasably holding said tray either in first or second of said positions, a solenoid carried by said tray, an operating connection between said solenoid and release rod, said release rod being in cooperative relation with said spring latch to operate the same only when said tray is in second position, whereby a first energization of said solenoid releases said tray from first position for movement under gravity to second position, and a second energization of said solenoid (1) releases said tray from second position and (2) operates said spring latch to release the same and permit said spring driving mechanism to operate said slide and return said tray to first position while simultaneously driving said feed screws to feed a shell into said tray as the latter arrives at first position.
